TRASH RECEPTACLE

E. Burton Benjamin, Highland Park, Ill., assignor to Loma
Industries, Fort Worth, Tex., a corporation of Texas

Filed Apr. 20, 1964, Ser. No. 79,588

Term of patent 14 years

(Cl. D58—17)

FIG. 2.

I claim:

The ornamental design for a trash receptacle, as shown.
